UNITED STATES PATENT OFFICE.

CARL AUGUST MÜLLER, OF WITZENHAUSEN, GERMANY.

SAFETY LOCK.

Application filed March 9, 1921. Serial No. 450,894.

To all whom it may concern:

Be it known that I, CARL AUGUST MÜLLER, a citizen of the German Republic, and residing at Witzenhausen, Werra, Germany, have 5 invented certain new and useful Improvements in Safety Locks, of which the following is a specification.

This invention relates to safety-locks, and more particularly to mortise locks of the 10 pin tumbler type, having more than one group of tumblers.

The object of the invention is to provide additional security in locks of the above type, and with this object in view the invention 15 consists substantially in providing such a lock with tumblers having any desired amount of movement or stroke, and disposed in any desired order of succession in two or more groups arranged on opposite 20 sides of a central plane of the key barrel.

By a symmetrical arrangement of the tumbler groups this lock may be constructed to be operated from either side. The separate tumblers may be grouped in any desired 25 manner, for instance side by side, one above the other, or one behind the other, or they may occupy any one of these positions, or several or all simultaneously. Each main group of tumblers may be duplicated 30 with the same tumblers arranged in a reversed order, so as to provide additional security or reinforcement.

Owing to the arrangement of a larger number of suitable tumblers thus rendered 35 possible by the invention with any desired amount of movement even within a comparatively small space, safety combinations may be provided even for the smallest locks, which are secure and strong to a degree not 40 attainable heretofore. The keys for the locks may be of any desired shape, each key being adapted to the arrangement of the groups in the lock for which it is intended and being provided with suitable notches 45 rises or steps to correspond with the tumblers or their plungers so that it may be used for actuating all the groups of tumblers simultaneously.

Three modes of carrying the invention in 50 to effect are shown by way of example in the accompanying drawings, in which:

Figs. 1 to 3 show in various sections, one form of lock constructed in accordance with this invention with a suitable key of H-shaped section, the key also being shown in perspective in Fig. 3.

Figs. 4 to 6 are similar views of a modified lock, the key for which is of substantially triangular section, whereas

Figs. 7 shows in section a form of lock for 60 which a grooved and notched cylindrical key is used.

In the first mode of carrying the invention into effect, illustrated by Figs. 1 to 3, two groups of tumblers *a* and *b* are arranged 65 symmetrically one on either side of the central plane. The tongues *c* and *d* of the key correspond to these two groups of tumblers. Thus when the lock is operated from one side, the tongue *c* of the key will effect the 70 adjustment of the group of tumblers *b*, whereas the tongue *d* will effect the adjustment of the group *a*. If, however, the lock is to be adapted to be operated also from the opposite side, the key must be provided with 75 tongues *e* and *f* of which the tongue *e* actuates the group of tumblers *b* and the tongue *f* actuates the group *a*.

With a reversible lock of this kind the notches or rises of the adjacent tongues *c*, 80 *e* and *f* of the key are arranged in reversed order as indicated by the numerals in Figs. 2 and 3 so that when the key is inserted from one side or the other the rises will correspond with their respective tumblers.

Additional groups of tumblers *a'* and *b'* may be provided, arranged so as to correspond with the tongues *e* and *f* of the key, so that all the tongues and key notches or 90 rises come into operation.

The tumblers are moved into their locking position by springs *g* and are set and manipulated by the tongue of the key through the medium of plungers *h*.

The lock shown in Figs. 4 to 6 is modified in two respects. In the first place the members *h* are not rod-shaped as in the form above described, but are angular, that is to say they are provided with off-set portions *i* which project into the path of the tongue or the key, the part *h* acting on the tumblers. The provision of the off-set portions enables more tumblers to be distributed over the same depth of lock. This is clearly shown in 105 Figs. 4 to 5. In the form illustrated four tumblers are provided on each side of the central plane of the key, the plungers for two of which are provided with longer off-set portions *i* than those for the other two. 110 Although the key shown is substantially triangular in section, it may be H-shaped,

or it may be of any other shape, the shape depending upon the length of the off-set portions *i* of the plungers *h*. The key is further so designed that, when the lock is operated from one side, the key steps or rises *c* adjust the tumblers *b*, and the steps *d* act on the tumblers *a*. If the lock is to be adapted to be operated also from the other side, double the number of key steps must be provided, but in a reversed order for each additional group of tumblers, so that the additional key steps *e* (Fig. 6) act on the tumblers *b* (Fig. 4), and the key steps *f* act on the tumblers *a*. With this form of lock further additional groups of tumblers, corresponding with the tumbler groups *a'* and *b'* in Fig. 1, may be provided, in which case the key would be correspondingly adapted to that shown in Fig. 3.

20 A cylindrical key may be used, as shown in Fig. 7, in which case the steps or notches are provided in grooves in the key stem. As shown the steps *c* actuate the group of tumblers *b* and the steps *d* actuate the tumblers *a*. If the lock is to be operable from either side, further steps or notches *e*, corresponding with the steps *c*, and steps *f* corresponding with the steps *d*, but arranged in a reversed order, must be provided. The number of the tumblers in this form of lock may be increased as in the first form shown in Figs. 1 to 3.

Further the plungers *h* may be constructed as shown in Fig. 4.

35 In the forms of lock illustrated, as well as in all other locks belonging to the category in question, any desired number of tumblers may be provided, but the tumblers however, in the case of locks which are adapted to be operable from either side, must be in groups arranged symmetrically in relation to the central plane of the key. The number and shape of the tumblers, and of their plungers *h* or *h*, *i* may be varied as desired and also the amount of movement or order may be modified.

50 As the tumblers may be arranged opposite to each other, above one another, behind one another, or side by side, or in several or all these positions simultaneously, an increased security is obtained with locks which can be locked from one side only, such as for instance locks for strong boxes, money boxes, trunks and the like. In such cases the arrangement of the tumblers need not be symmetrical. In such locks, if for instance they are provided (as in Fig. 1) with four groups

of tumblers *b*, *b'* *a'* and *a*, the tumbler groups *b* and *b'* may consist of any suitable tumblers arranged in any desired order. 60 Such locks, for instance those according to Fig. 1, may comprise for example only some of these groups, e. g., the groups *b* and *b'*, or the groups *a'* and *a* with any desired tumblers in any desired order, the numerous various groups which are possible being arranged at any desired distances apart, and consisting of any desired number of tumblers, for instance of 2, 3, 4, 5, 6 or more tumblers. 65 Any desired form of key may be used, the various tongues or sections of which, in the case of locks adapted to be operable from either side, being arranged symmetrically in relation to each other, although, in the case of locks which are operable from one side only, the various tongues or sections may occupy 70 any desired position, and need only correspond with their respective groups of tumblers. The tumblers and plungers used in connection therewith may be of any desired 75 shape, and be made in one or more parts.

What I claim, is:

1. In combination, a lock of the pin tumbler type having rows of tumblers with their plungers all arranged in parallel planes, 85 some rows being disposed on one side and some on the opposite side of and in parallel relation to the central vertical plane of the keyway, and a multiple-bearded key having beards corresponding in number to the number of rows of tumblers, substantially as set forth.

2. A lock of the pin tumbler type specified in claim 1, wherein the rows of tumblers are arranged symmetrically in relation to the central vertical plane of the keyway in such a manner that a manipulation of all the tumblers by means of the same key can be effected from either side, of the lock, substantially as set forth.

3. A lock as of the pin tumbler type specified in claim 1, having two main rows of tumblers and in which each main row is duplicated by similar tumblers arranged in a reversed succession so as to serve as a reinforcement row, substantially as set forth.

In testimony whereof I have hereunto set my hand in the presence of two subscribing witnesses.

CARL AUGUST MÜLLER.
